UNITED STATES PATENT OFFICE

CARL H. HOFFSTETTER, OF ERIE, PENNSYLVANIA, ASSIGNOR TO ODIN STOVE MANUFACTURING COMPANY, OF ERIE, PENNSYLVANIA, A CORPORATION OF PENNSYLVANIA

METAL PLATE STRUCTURE

Application filed April 15, 1929. Serial No. 355,127.

In many devices, such as metal furniture including stoves, it is desirable to furnish the article with an exterior frame plate. In the stove art, such a plate is illustrated by the 5 surrounding base plate which carries the stove body and to which the legs are attached. In securing the body and legs to this plate it has been common, in the past, to use stove bolts and the heads of these stove bolts are 10 arranged outside the plate. In order to perfect the finish of the stove it has not been uncommon to conceal these bolts with covering plates and by other devices. In the present construction, the bolts are rigidly secured 15 to the inner surfaces of such plates and the parts within the plate are secured to the bolts in the usual manner by nuts, thus providing for the convenient assembly of the devices and at the same time providing an unbroken 20 outer surface of the plate for finishing in any desired manner. Features and details of the invention will appear from the specification and claim.

A preferred embodiment of the invention 25 is illustrated in the accompanying drawings as follows:—

Fig. 1 shows a front elevation of a stove.

Fig. 2 a section on the line 2—2 in Fig. 1.

Fig. 3 a view of the parts before assembly.

30 Fig. 4 a detached view of the bolt before it is secured to the plate.

Fig. 5 an enlarged view of the bolt as secured to the plate.

35 Fig. 6 a view indicating the manner of welding.

1 marks the stove body, 2 the surrounding base plate, and 3 legs for the stove. Securing bolts 4 have heads 5. These heads have a 40 flat surface 6 facing the direction of the bolt and a convex surface 7 opposite the bolt shank.

This form of bolt may be welded to a plate in the manner generally illustrated in Fig. 6.

45 8 marks an electrode having a bolt-receiving socket 9, the electrode having a surface 10 engaging the under-surface 6 of the bolt head making practically a contact throughout this surface. The plate 2 is fixed on the convex surface of the head and an electrode 11

engages the upper surface of the plate and presses the same down on the convex head.

It will readily be seen that the surfaces are large at all points except at the point of contact of the convex surface 7 and the plate. 55 The metal here fuses and as the head de-presses it rapidly increases the current capacity and the welding area expands usually to a diameter about equal to that of the bolt.

With the bolt so attached the bolts may be 60 passed through openings on the inner parts of the structure as at openings 12 on the body and 13 on the legs. These openings where arranged in corner structures should be 65 slightly elongated so as to permit the short projecting bolts to be passed through the openings. Nuts 14 are provided clamping the parts together. The bolts give a rigid construction, the heads slightly bracing them laterally and leaving the outer surface unobstructed so that these surfaces may be finished in any manner desired, thus saving 70 cover plates and other devices for this purpose. Thus a more rigid structure is provided and a structure of less parts. 75

What I claim as new is:—

In an article of manufacture, the combination of an exteriorly faced corner plate; inwardly projecting bolts on each extension of the corner plate having heads with their 80 centers welded to the inner surface of the plate, the axes of the bolts being at right angles to the corner plate extensions and the axes of the bolts on one extension being in converging relation with the axes of the bolts on the other extension of the corner plate; and a corner member having extensions from the corner, one extension being rigid relatively to the other and having 85 elongated slots through which the bolts extend. 90

In testimony, whereof I have hereunto set my hand.

CARL H. HOFFSTETTER.
